UNITED STATES PATENT OFFICE

1,962,554

ELECTRIC WIRING SYSTEM

Martin J. De Mask, Pittsfield, Mass.

Application September 23, 1931, Serial No. 564,631

3 Claims. (Cl. 247—3)

This invention relates to wiring systems in which plug receptacles are employed to extend over a wall or ceiling and provided at intervals with openings in which a plug may be inserted so that current may be taken off at various points to provide lights or operate tools.

The primary object of the present invention is to provide a conduit or plug receptacle of such form that the current-conducting elements will 10 be carried by a cap or cover which may be easily fitted upon or removed from the main casing of the receptacle.

Another object of the invention is to provide novel means for connecting the ends of sections 15 of the conduit or receptacle and the invention also seeks generally to improve the construction of devices of this type, reduce the cost of the same, and facilitate the installation thereof. The invention is illustrated in the accompanying drawings and will be hereinafter fully described, the 20 novel features being particularly defined in the appended claims.

In the drawings:

Fig. 1 is a side elevation of a portion of a plug 25 receptacle embodying the invention.

Fig. 2 is a transverse section on the line 2—2 of Fig. 1.

Fig. 3 is a view similar to Fig. 2 but showing 30 a modification.

Fig. 4 is a view similar to Fig. 2 but showing a further modification.

Fig. 5 is a bottom plan view of the conduit.

Fig. 6 is a detail perspective view of a portion 35 of the core and conductor strips shown in Fig. 2.

Fig. 7 is a detail perspective view of a portion 40 of the core shown in Fig. 3.

Fig. 8 is a detail perspective of a portion of the conductor bar shown in Fig. 3, as the same appears before it is mounted upon the core.

Fig. 9 is a side elevation showing means for coupling the adjacent ends of sections of the conduit.

Fig. 10 is a view, partly in side elevation and partly in longitudinal vertical section, of the structure shown in Fig. 9.

Fig. 11 is a detail elevation of a portion of the structure shown in Fig. 9, the cover being removed from the conduit.

Fig. 12 is a transverse section on the line 12—12 of Fig. 9.

Fig. 13 is a transverse section similar to Fig. 2, but showing a further modification.

Fig. 14 is a transverse section showing the conduit arranged to permit the insertion of a plug 55 through its sides.

Fig. 15 is an elevation, with parts in section, of another modification.

Fig. 16 is a section on the line 16—16 of Fig. 15.

The apparatus of the present invention includes a conduit or receptacle 1 which is constructed in sections having a standard length of ten feet although they may be longer or shorter. These sections are preferably stamped from sheet metal and given the form shown clearly in Fig. 2, and are secured to a wall, partition, or ceiling 60 in any convenient or preferred manner. The sides of the conduit sections are shaped at their free edges to form beads 2 which extend the full length of the sections and tend to resist buckling of the sections and also furnish means whereby 70 the cover may be engaged and held in place. The conduit sections are shown in Figs. 2 and 3 without lining but in Fig. 4, which shows a conduit section 3 of less depth than the section shown in Figures 2 and 3, a lining 4 of some light insulating material is provided and extends over the entire inner surface of the section. A cover 5 is provided and this cover is also made in sections having the same length as the sections of the conduit or receptacle and has its edge portions formed into beads or flanges 6 which are adapted to spring over and ride into gripping engagement with the beads 2 of the receptacle, as 75 shown clearly in Figs. 2, 3 and 4. The cover is stamped from sheet metal and at intervals in its 80 length, openings 7 are provided therein, these openings being covered or closed by knock-out discs as is the usual practice in the art. Each section of the cover has a core therein and this core is permanently attached to the cover in any 85 convenient manner. In the form shown in Fig. 85

the core is formed of "Bakelite" or some other similar moldable insulating material and includes a central body bar or strip 8 with an upper flange 9 extending between the sides of 90 the lining 10 which is provided along the sides of the receptacle while at the lower end or edge of the bar 8 is a flange 11 extending from both sides of the bar and provided with openings 12 therethrough within the area of the openings 7 100 in the cover, as shown clearly in Fig. 5. Extending along the sides of the core body 8 are conductor strips 13 which may be embedded in the core during the molding of the latter and these conductor strips are intended to be closely engaged by the prongs of a plug which may be inserted through the openings 12, the body of the plug, which is generally of insulation, being received within the opening 7 so that a close engagement of the plug with the receptacle may be 110

attained. If it be intended to use plugs having flat straight prongs or circuit-closing fingers, clips 14 may be provided to insure and maintain the proper engagement of the prongs with the 5 conductor bars. These clips may have one side embedded in the core, back of the conductor strip or bar, and its outer portion formed into a resilient finger which will normally lie against the conductor strip and will, therefore, force the 10 prong of the plug to the strip and hold it in firm engagement therewith. After the conduit or receptacle has been secured in place, the cover is merely slid over the beaded edges of the receptacle and will be firmly held thereon 15 through the resilient frictional engagement of the beads upon the receptacle and cover, as will be understood. It will be noted that the core is permanently attached to the cover and, therefore, when the cover is fitted in place the core 20 is housed within the receptacle and, vice versa, removal of the cover will withdraw the core from the receptacle, the paper lining 10 remaining in the receptacle. The installation of the device is thus facilitated and inspection and re- 25 pairs may be expeditiously made.

In Fig. 3, the core is formed of a central strip 15 of press-board and an outer section of the same material which is folded upon itself to provide an inverted U-shaped body 16, with 30 flanges 17 extending in opposite directions from the sides of said body. This inverted U-shaped body is placed over the strip 15, as shown in Fig. 3, and the conductor bars 18 are disposed against the opposite sides of said body and are formed 35 at intervals with prongs or teeth 19 which may be bent laterally and inserted through openings 20 provided therefor in the sides of the body 16 and clinched against the inner surface of the body by being bent through their impact against 40 the strip 15, as will be readily understood upon reference to Fig. 3. Or the prongs may be clinched against the inner surface by other means, in which case, the strip 15 will be placed in position after the prongs are clinched against 45 the inner surface of the body. If desired, the central strip may be omitted. A lining 21 is se- 50 cured in the casing at the sides of the core in this form of the device and a partition 22 is extended between the sides of the lining and rests upon the body 16, as shown. Between the 55 bottom or back of the receptacle and the partition 22 or the flange 9, as the case may be, there is provided a chamber or way 23 through which extra wires may be run so as to provide for future extensions of the system. The flanges 17 of the core shown in Fig. 3, have openings 24 therethrough to permit the insertion of the prongs of a circuit closing plug, it being noted that in all forms of the invention the openings 60 12 or 24, as the case may be, are so located that a finger or prong passing therethrough will be guided directly into engagement with the adjacent conductor strip.

In Fig. 4 is shown a receptacle 3 which is of 65 less depth than the receptacle shown in Figs. 2 and 3 and which is provided with a lining 25 of insulation which covers the entire inner surface of the receptacle. This form of the invention omits the ways 23 shown in Figs. 2 and 3 70 but otherwise is the same in all essential respects as the form shown in Fig. 3, and it is to be noted that in all three forms removal of the cover effects removal of the core but the paper lining remains in the receptacle.

75 In some instances it may be desirable to use

plugs having flat straight prongs or circuit closing fingers in connection with the structures shown in Figures 3 and 4. In this event, the clips 14, shown in Figure 2, would be used in the same manner with the plug receptacles shown in Figures 3 and 4. Instead of being embedded in the U-shaped body 16, the clips 14 would be riveted to the conductor bars 18.

It is, of course, desirable that means be provided to couple the ends of adjacent lining sections in such a manner that there will be no interruption to the flow of current. For this purpose I provide the structure shown in Figs. 9 to 12, in which figures conduit sections 1 are shown with covers 5 engaged thereon, as previously shown and described. The core 26 is indicated in Fig. 10 as filling the receptacle and the conductor strips are shown on the sides of the core very clearly in Fig. 10. A coupling sleeve member 27 is provided of the same cross sectional outline as the receptacle 1 and it is slightly enlarged at its ends, as indicated at 28, whereby it may fit closely over the ends of the aligned sections and be held against endwise movement thereon. This coupling sleeve is formed with 100 beads 29 along its side edges and a cover 30 is provided to engage over the beaded sides of the sleeve, as shown in Fig. 12. In connecting the ends of the sections of the conduit, wires 31 are soldered to the ends of the conductor strips 30' shown in Fig. 10, and are then brought together and their meeting ends twisted together as shown at 32. The wires are then wrapped with tape, as indicated at 33, after which the cover 30 is sprung into place. As shown most clearly in Fig. 11, the 105 ends of the sleeve member 27 are cut away in their lower portions, as indicated at 34, so that the cover 30 may overlap the beads of the respective receptacle sections and abut the end of the cover 5 engaged with the receptacle. This de- 110 scribed form of coupling is very inexpensive and permits the ends of aligned sections of the conduit to be very easily, effectually and expeditiously joined so as to transmit the current through any desired length of conductors. 115

In Fig. 13 is shown a receptacle 1 of the same form as that shown in Figs. 2 and 3, and the cover 35 is shown with a core 36 very similar to the core 8 shown in Fig. 2. The conductor strips 37 are embedded in the sides of the core but in 120 this form of the invention the clips 14 are omitted. A lining 38 is secured in the receptacle and is of such dimensions that a passage or way 39 is provided at the back of the receptacle for extra wires, a lining 40 being applied to the inner sur- 125 face of the sides of this way, as clearly shown. A strip of lining paper 50 is secured in the cover and extends the full length thereof in this form of the invention and this strip with the core is removed when the cover is removed.

In Fig. 14, I have shown the receptacle or conduit section 41 provided with knock-out openings 42 in its sides. Beads 43 are provided along the free side edges of the conduit and the cover 44 is engaged over these beads in the manner 140 previously described. In this form of the invention, the core comprises two side members 45 and cross bars 46 and 47, the bar 46 being spaced from the edges of the side members 45 so as to provide a way adjacent the cross web of the cover 145 for extra wires. Openings 48 are formed in the side members 45 at the upper and lower sides of the cross bar 47 and the conductor strips 49 are embedded in the upper and lower sides of said cross bar, as shown. This arrangement provides 150

for the insertion of plugs through the sides of the conduit and may be found highly desirable and convenient in odd situations where the first described forms would be inconvenient. In this 5 form of the invention, the entire plug-receiving body is removed with the cover, leaving the conduit section bare.

In Figs. 15 and 16, the conduit section has a paper lining 51 secured therein and a strip 52 of paper is secured on the inner side of the cover. 10 The core 53 is secured to the cover over the paper strip 52 and conductor bars 54 are embedded in the sides of the core flush with the surfaces thereof. Openings 55 extend longitudinally through 15 the core to receive bare copper switch or feeder wires 56 which are fished through the openings and passed from one conduit section to another section or may terminate at any section. Between conduit sections, tubes 57 of insulation are 20 disposed around the wires 56 and have their ends fitted in the aligned openings 55, as shown in Fig. 15. Coupling sleeves 27 and covers 30 are engaged over the ends of the aligned conduit sections. Openings for the insertion of plugs are, 25 of course, provided through the cover and the paper strip 52. Of course, covered or insulated wires may be fished through the openings 55, the tubes 57 then being unnecessary between the sections.

20 From the foregoing description, taken in connection with the accompanying drawings, it will be seen that I have provided a very simple, compact and easily installed apparatus which will provide for the plugging in of lighting fixtures or 25 outlets at various points.

Having thus described the invention, what I claim is:

1. Apparatus for the purpose set forth comprising a receptacle, a cover engageable over the receptacle, a core fixed upon the cover and comprising a central strip and a covering body extending over said strip and at the sides of the same and spaced from the sides thereof, and conductor strips fitted upon said covering body and provided with prongs insertable through the body and bendable by contact with the central strip. 80

2. Apparatus for the purpose set forth comprising a receptacle, a cover engageable over the receptacle, a core carried by the cover and including an inverted U-shaped body extending longitudinally of the cover, and conductor strips having prongs passed through and clinched upon opposite sides of said body, the core having openings at the cover and the cover having openings aligned with the openings in the core whereby to permit the insertion of a plug to engage the conductor strips. 90

3. Apparatus for the purpose set forth comprising a receptacle, a cover engageable over the receptacle and resiliently held thereon, a core fixed upon the cover and housed within the receptacle when the receptacle and cover are engaged, said core including a central strip set on edge and a covering body extending across the inner edge of said strip and over and spaced from the sides of the same, and conductor strips fitted upon the sides of the covering body and provided with 105 prongs insertable through the body and bendable by contact with the central strip, the core having openings and the cover having openings aligned with the openings in the core whereby to permit the insertion of a plug to engage the conductor 110 strips. 100
